UNITED STATES PATENT OFFICE.

GIUSEPPE PALOMBO, OF SOUTH GREENSBURG, PENNSYLVANIA.

DESIGN FOR A HEEL-PLATE.

52,584.

Specification for Design.

Patented Oct. 15, 1918.

Application filed November 10, 1917. Serial No. 201,391. Term of patent 7 years.

To all whom it may concern:

Be it known that I, GIUSEPPE PALOMBO, a citizen of Italy, residing at South Greensburg, in the county of Westmoreland and State of Pennsylvania, have invented a new, original, and ornamental Design for Heel-Plates, of which the following is a specification, reference being had to the accompanying drawing, forming a part thereof.

Figure 1 is a perspective view of a heel plate, showing my new design; and

Fig. 2 is a bottom plan view.

I claim:

The ornamental design for a heel plate, as shown.

GIUSEPPE PALOMBO.
